CLAIM

The ornamental design for a butterfly toy balloon, substantially as shown and described.

DESCRIPTION

FIG. 1 is a top plan view of a butterfly toy balloon showing my new design, the side opposite being a mirror image;

FIG. 2 is a front elevational view thereof;

FIG. 3 is a rear elevational view thereof;

FIG. 4 is a side elevational view thereof, as viewed from the right in FIG. 1; and

FIG. 5 is a side elevational view thereof, as viewed from the left in FIG. 1.

FIG. 1

FIG. 2

FIG. 3

FIG. 4

FIG. 5
